UNITED STATES PATENT OFFICE.

FREDERICK NOEL MACKAY, OF CROYDON, ENGLAND.

AIR OR GAS PUMP FOR REFRIGERATING-MACHINES.

SPECIFICATION forming part of Letters Patent No. 746,856, dated December 15, 1903.

Application filed June 23, 1902. Serial No. 112,885. (No model.)

To all whom it may concern:

Be it known that I, FREDERICK NOEL MACKAY, engineer, a citizen of England, residing at The Limes, 34 Clyde road, Croydon, in the county of Surrey, England, have invented a certain new and useful Air or Gas Pump for Refrigerating-Machines, (for which I have applied for a patent in Great Britain, No. 24,048, dated November 26, 1901,) of which the following is a specification.

This invention relates to an apparatus for utilizing the force produced by the expansion of vapors or gases condensed to a liquid or partly-liquid state in the condenser of an ice-making or refrigerating-machine as motive power for driving such part of the machine as may be best adapted to economically use the same; and the object of the invention is to improve and simplify the construction of this class of apparatus generally.

Although all gases or vapors capable of being condensed to a liquid state are available for the purposes of this invention, I prefer to use carbon dioxid as the refrigerating medium, because this gas in expanding from the liquid state evaporates and expands to a greater degree in cooling than perhaps any other gas or vapor used in ice-making machinery and is consequently very well adapted for doing economical work during expansion which is afterward utilized in compressing the gas from the expanded or gaseous to the liquid state.

The apparatus which I employ for the above purpose may also be employed for obtaining power from vapors or gases that have been condensed by other apparatus than that of an ice-making machine, as the chief feature of my apparatus consists in the means adopted for expanding and exhausting the expanded gases in such manner as to insure the maximum amount of power being derived therefrom and also in the means adopted for preventing the freezing of the vapors in the passages in and about the valves or tappets employed—namely, by causing the incoming and the outgoing vapors to enter and leave the pump by one and the same channel or port, whereby any frozen matter formed by the expanding gases will be removed by the higher temperature of the compressed gases, the exhaust-valve being rendered free to

open inward directly the expanded gas is reduced to the pressure of that already in the evaporator or cooler of the machine, so that 55 excess of low temperature is thereby prevented, and thus the chance of freezing up due to excessive lowness of temperature is reduced to a minimum. Furthermore, the temperature of the expanding-cylinder is by 60 the construction of the apparatus prevented from becoming unduly lowered by the fact that while expansion takes place on the one side compression is effected on the other side of one and the same piston. Also as the incoming gases or vapors from the evaporator are by preference made to enter the compressor by passing through a hollow piston-rod in the expanding-cylinder a further interchange of temperature takes place, thus 70 also preventing an undue lowness of temperature within the expanding-cylinder.

It will be obvious that my herein-described apparatus can be operated with other refrigerating gases or vapors than carbon dioxid, 75 though for the reason set forth I believe that the best results are obtained by using the gas specified.

I will proceed to describe, by way of example, a construction of apparatus which is 80 shown on the accompanying drawings, in which carbon dioxid is assumed to be the refrigerating medium employed.

Figure 1 shows a vertical section through the pump-cylinder and parts connected therewith on line 1 1, Fig. 5. Fig. 2 shows a section on line 2 2, Fig. 1. Fig. 3 shows a section through the cylinder, taken at right angles to that at Fig. 1. Fig. 4 shows a section on line 4 4, Fig. 5, which shows a cross-section on line 5 5, Fig. 3. Fig. 6 shows a front elevation, partly in section, of the entire machine. Fig. 7 shows a side view thereof. Figs. 8 and 9 show enlarged details of the several devices.

The compressor-cylinder 1 is made at the same time to constitute an expansion-cylinder in which the work of the expanding highly compressed and condensed gas or vapor is performed, the space above the piston 2 constituting the compressor-chamber, while the space below the piston constitutes the expansion-cylinder into which the gas coming from the condenser issues, as will be pres-

ently described. Separated from the expansion-chamber by a suitable partition 3, with packing, through which the piston-rod 4 passes, is a lower chamber 5, into which the 5 fully-expanded gas coming from the cooler of the machine passes on its way to the compressor-chamber. For this purpose the upper part 4^x of the piston-rod 4 is enlarged and formed tubular and its upper open end 10 is formed with a coned seating for a valve 6, which is held closed by a spring 7. At the lower end of the tubular part 4^x is a lateral opening 8, which always communicates with the chamber 5, into which the fully-expanded 15 gas passes, as will be presently described. Thus, on the downstroke of the piston 2 and consequent formation of a partial vacuum above it, the gas will pass from chamber 5 through opening 8 into the tubular piston-rod 20 and forcing open the valve 6 will pass into the cylinder above the piston. On the upstroke of the latter it will compress the charge of gas above it (valve 6 being then closed) and force it through the valve 9 into the chamber 10, communicating with the condenser, 25 as will be presently explained.

In order to insure a perfect gas-tight working of the piston 2, it is preferably constructed, as shown—namely, with a cup-leather packing 11, fitting the enlarged head of the piston, as shown—and secured by a screw-nut 12 and lock-nut 13, both screwed onto an external thread 14 on the piston-rod. It will be seen that the upper end of the piston with its valve is made to fit closely up to the under side of the valve 9 and its seat 47, just short of actual contact at the end of the upstroke, so that the whole of the charge compressed by the piston will be forced 35 through the valve 9 into chamber 10, thus preventing any opposition against the next upstroke of the piston and consequent waste of power due to the re-expansion of any gas remaining in the cylinder on the downstroke 40 of the piston.

To the side of the cylinder 1 is fixed a double-valve apparatus 15, communicating therewith by a single passage 16. This double-valve apparatus is constructed and operates 50 as follows: The valve-chamber 17 communicates with the condenser of the machine by a pipe 18, from which the condensed gas passes into the chamber at a very high pressure, such as sixty atmospheres. In this chamber is an 55 inlet-valve 19, closing an opening 20, leading, first, into the upper end of the lower valve-chamber 21 and thence through passage 16 into cylinder 1, so that when 19 is momentarily opened, as will be presently described, a 60 certain quantity of the condensed gas will flow through 20 and 16 into the cylinder. The opening of the valve 19 is timed to take place when the piston 2 has just completed its downstroke, so that as the piston receives 65 its upstroke from the crank-shaft of the machine the admitted charge of gas in expanding below it acts as motive power in assisting

in effecting the upstroke of the piston for compressing the charge admitted above it, as described. The lower valve-chamber 21, 70 which, as before stated, also communicates with the cylinder through the passage 16, contains a valve 22, closing the communication between passage 16 and a pipe 23, leading to the cooler of the machine. When the piston 2 75 commences its downstroke, valve 22 is opened, as will be presently described, and the partially-expanded gas below the piston which, however, is still at a pressure of, say, twenty atmospheres, escapes through 16, 22, and 23 80 to the cooler. The gases in expanding during the upstroke of the piston will of course be reduced in temperature, and although the fully-expanded and comparatively warm gases passing in through chamber 5 and tubular piston-rod 4^x will to a certain extent 85 counteract such decrease of temperature, yet the gases passing off through passage 16 may still be sufficiently cold to freeze the particles of oil carried with them, and thus obstruct the 90 passage. I prevent this, however, by causing the condensed gases, which are at a higher temperature, coming from chamber 17 to pass into the cylinder through the same passage 16 through which the expanded gases escape, 95 so that the passage is warmed thereby and the deposit of any frozen oil particles in it from the escaping expanded gases will be prevented.

As the valve 19 is subject to considerable 100 downward pressure by the entering condensed gas, I relieve it to a certain extent of such pressure by forming it with an upward extension 19^x, passing up through a gas-tight packing 24 into a chamber 25, that communicates by 105 a passage 26 with the upper end of the lower valve-chamber 21, as shown at Fig. 2, so that the upper end surface of the valve-stem is only subject to the pressure in this valve-chamber. The chamber 17 is divided by a 110 partition 27, through which the valve-stem works into an upper and lower compartment which communicate with each other by a passage 28, opening into the upper compartment at a point somewhat above the partition, so that the oil coming in with the 115 condensed gas will leak down between the valve-spindle and partition into the lower compartment, where it will lubricate the actuating cam-spindle 29^x, while the gas will pass 120 down through the passage 28. The valve 19 is opened by the revolving cam 29, whose spindle receives rotary motion through toothed gear 30 from the cam-spindle 31 of the discharge-valve 22, driven by a chain-wheel 32 125 and pitch-chain from the crank-shaft, so as to revolve synchronously therewith.

For enabling the supply of condensed gas to the cylinder 1 to be regulated to any degree required the cam 29 is made tapering, 130 as shown at Fig. 2, and is capable of being moved longitudinally relatively to the valve-spindle by means of a hand screw-spindle 33, so as to increase or decrease the extent to

which the valve is raised by the cam and the duration of its opening. As the packing 34 in the stuffing-box of the cam-spindle is subject to the high pressure of the gas coming from the condenser, the packing is divided into two parts, as shown, between which is a lantern-piece 35, communicating, by means of a channel 36, with the channel 26, leading to the valve-chamber 21, so that any gas and oil leaking past the inner part of the packing 34 will find its way through 36 and 26 into 21, and thus leakage through the outer part of the packing 34 will be prevented.

It will be seen from the above-described arrangement of the discharge-valve 22 that should the condensed gas admitted to the cylinder below the piston 2 in expanding become less in pressure than that within the cooler of the machine the said valve will open automatically and in allowing the gas to pass from the cooler to the cylinder 1 the pressure will be equalized, thereby preventing an undue lowness of temperature in the cylinder. The oil that comes over with the gas from the condenser will by the chilling of the expansion-cylinder 1 be caused to remain to a great extent in the latter and will lubricate the cup-leather packing of the piston 2 and that of the partition 3. This partition and packing is secured in position by a lantern 37, which in its turn is secured by the gland 89 of the stuffing-box to be presently described. The piston-rod 4 works through a cup-leather 39, held in the partition 3 by a ring 38, secured by screws 42.

The lantern 37 is connected to the stuffing box gland 89 by a rotatable connection consisting of a groove 40, in which the thickened end 41 of the lantern is held by grooves and pins 43.

In order to prevent an undue accumulation of oil in the expansion-chamber of the cylinder, I provide a discharge-passage 44 just above the partition, through which the oil as it collects over the partition flows into a chamber 45, formed in the cylinder-casting. From this chamber the oil is allowed to pass down into the bottom chamber 5 through a passage 46, that is closed and regulated by a stop-cock 81. As by this means there will be an accumulation of oil in the bottom of chamber 5, as indicated in Fig. 1, in close contact with which the expanded gas will pass on its way through opening 8 and up the hollow piston-rod to the compressor-space of the cylinder, the gas will thereby be made to take up sufficient of the oil to convey it to the compressor-chamber, and thereby lubricate the parts thereof as described and make good the quantity of oil discharged with the compressed gas.

For readily ascertaining the amount of oil in the chamber 5 there is provided at the lower part thereof a gage-glass 52', which is fitted into a small chamber 53', formed at the side of the pump-casting, with sight-holes 54'. The ends of the gage-glass are fitted with

grooved plugs 55', fitting the bore of chamber 53' and pressed tight onto the ends of the glass by the screw-cap 56'. The plugs have a central passage 57', communicating with the interior of the glass and with a transverse passage 58', communicating with the circular channel 59', formed by the groove of the plug, which channels in their turn communicate with the openings 60', leading into the pump-chamber.

The stuffing-box at the lower end of cylinder 1, through which the piston-rod 4 works, consists, first, of an outer gland 89, screwed into the neck of the cylinder and having a grooved flange 89^x with packing for making a gas-tight joint against the end of the cylinder-neck; secondly, a cup-leather 90, making a tight joint against the piston; thirdly, a ring 91, screwing into the internal thread of gland 89 for keeping the cup-leather in position and making a gas-tight joint therewith; fourthly, a packing consisting, by preference, of two rings of leather 92, between which are rings of elastic material 93, and, lastly, an inner gland 94, screwed into the outer gland 89, so as to tighten up the packing 92 93. This inner gland is loosened when the machine is working, because at that time the gas-pressure causes the cup-leather 90 to make a gas-tight fit against the piston-rod; but when the machine is standing and the pressure is comparatively small the cup-leather may not fit sufficiently tight to prevent a leakage of gas or oil between it and the piston-rod, and to prevent any such leakage at that time the gland 94 is then screwed up, so as to tighten the packing 92 93 against the piston-rod.

As shown in the section, at Fig. 3, the casting of the pump-cylinder 1 is formed with a suction-chamber 48 on one side thereof and with a discharge-chamber 49 on the other side, these chambers being preferably formed in one casting with the cylinder in order to effect an interchange of temperature between them and conduct the heat of the compressed gas in chamber 49 to the pump-cylinder 1 to prevent the freezing of oil particles in said pump-cylinder due to expanded gas. The chamber 48 communicates at top by the regulating-valve 50 with the pipe 51 from the bottom of the cooler and at bottom by the opening 52 with the bottom chamber 5 of the pump-cylinder, so that on the piston 2 performing its downstroke the expanded gas and oil vapor carried thereby will flow down chamber 48 and through opening 52 into chamber 5, whence it will pass through the opening 8 into the tubular piston-rod to be compressed on the upstroke of the piston, as before described, the compressed charge flowing from chamber 10 through the opening 53, leading into the discharge-chamber 49, whence it passes through opening 54 and regulating-valve 55 into pipe 56, leading to the condenser.

In order to prevent the oil vapor carried by

the gas from passing off with the latter through the opening 54, a baffle-plate 57 is fixed in the chamber 49 between the openings 53 and 54, so that the oil vapor in striking 5 against such plate is deflected thereby and descends to the lower part of the chamber 49, where it is condensed by the cold interchanged between the lower end of the pump-cylinder 1 and the lower end of said chamber 10 49, the gas freed from the oil passing up on the other side of the baffle-plate and passes off through 54.

At the lower part of the discharge-chamber 49 is formed a small lateral opening 58, leading 15 into the bottom chamber 5 of cylinder 1, which opening is closed by a stop-valve 59" of a construction to be presently described, so that when required this valve is opened and more or less of the oil accumulated in 20 chamber 49 is allowed to flow back into the pump-chamber and thence into the suction-chamber 48.

The seat 47 of the compression-valve 9 is formed cup-shaped, as shown, so that a certain 25 quantity of the oil passing up with the gas will accumulate in it above the compression-valve and will thus prevent any downward leakage of the compressed gas through the valve when the piston performs its down-stroke, while any leakage of the oil will not matter, as it will only pass down onto the piston 2 and serve to lubricate the packing 11 thereon, to facilitate which small passages 59" may be formed in the piston.

At the one side of the pump-chamber is formed a small chamber 60, having attached to it a screw hand-pump 61 for forcing oil into the pump-chamber from the outside (for making good any loss, such as oil that may have leaked through the gland) should the oil there-in be deficient. The barrel 61 has for this purpose a screw-spindle 62 screwing through its cup-shaped upper end 63, which is filled with the oil to be supplied. This oil finds 45 its way down into the barrel 61 through longitudinal grooves 64, formed in the screw-spindle, the lower end of which has rotatably attached to it a plunger 65, that fits the bore of the chamber 60, which has a lateral opening 66 leading into the pump-chamber and closed by a stop-valve 67. When it is required to supply oil to the pump-chamber, the screw-spindle 62 is first screwed upward, so as to withdraw the plunger from the bore of chamber 60, thereby causing the oil to flow down from the cup 63 into this chamber. On then unscrewing the stop-valve 67, so as to open passage 66, and screwing the spindle 62 down again the plunger 64 will force the oil 60 into the pump-chamber, after which the stop-valve is closed again.

The stop-valve 67, as also all other stop-valves of the machine, is preferably constructed as follows: A screw-threaded spindle 65 67 has its inner end formed with a central recess 68, so that it seats with an annular edge over the opening. This spindle screws

through a gland 69", that is screwed into the cylinder-casting, and is secured by a lock-nut 70, having an annular groove on its under side filled with packing material, so as to prevent leakage past the screw-thread. The outer end of gland 69" has a coned recess, into which fits a correspondingly-shaped block 71, of suitable packing material, and on its outer screw-thread is screwed a socket-piece 72, so formed with a partition 73 as to press upon the packing 71 by means of a loose washer 74, and thereby form a gas-tight packing for the screw-valve 67. The stem of the latter extends through the partition 73 into the outer part of the socket-piece, which is closed by a screw-cap 75, having an annular groove filled with packing. It will be seen that by this construction all leakage past the screw stop-valve 67 is effectually prevented, first, by the packing 71, and, secondly, by the packed screw-cap 75. For opening or closing the screw-valve the cap 75 is temporarily removed. Fig. 8 shows the application of the same construction screw stop-valve to the valves 50 and 55 for controlling the suction and discharge to and from the pump-cylinder 1. The only difference in this application is that the part 69" instead of being screwed with its end into the cylinder communicates therewith by a lateral screwed branch 76 and has its other end connected by a gland with suitable packing to the pipe 51 or 56, leading in the one case from the cooler and in the other case to the condenser. Fig. 9 shows the same construction of valve applied as the expansion-valve 77, connecting the pipe 23 from cylinder 1 to the cooler-coil 78, Fig. 6. In this case the screw-valve has a small plug 79 fixed in it, which fits into the small passage 80 of the pipe 23, leading from the discharge-valve.

Figs. 6 and 7 show the general arrangement of the above-described machine for compressing and expanding gases or vapors for refrigerating purposes. The cylinder 1 is mounted on the top of a frame 91, at the bottom of which are concentrically arranged the condenser-coil 92 and the cooler-coil 78. From the lower end of the latter the pipe 51 leads up to the inlet-valve 50 of the suction-chamber of the compressor-cylinder, while the top of the condenser-coil 92 communicates by a pipe 56 with the discharge-valve 55 of the compressor-cylinder. From the bottom of the condenser-coil 92 the condensed gas passes up through the pipe 18 to the inlet-valve chamber 17 in order to do work in partially expanding in the cylinder, as before explained, the partially-expanded gas then passing from the discharge-valve chamber 21 through pipe 23 and expansion-valve 77 into the upper end of the cooler-coil 78.

The operation of the apparatus is briefly as follows: Expanded gas or vapor compressed by the piston in the cylinder 1 passes into the chamber 49. From the chamber 49 the compressed gas passes through the pipe 56 to the

upper end of the condenser-coil 92, where its heat is extracted and it is condensed by a cooling medium surrounding said coil. The condensed or liquefied gas then passes from the lower end of the condenser-coil 92 by the pipe 18 to the chamber 28 and partially expands in said chamber beneath the piston of the apparatus, thus aiding in the operation of said piston. The partially-expanded gas in the chamber 28 then passes by the pipe 23 to the upper end of the cooler-coil 78, where it entirely expands, thus cooling the contents of the receptacles adjacent to said cooler-coil. From the lower end of the cooler-coil 78 the expanded gas passes by the pipe 51 to the upper end of the chamber 48, then down through the chamber 48, and into the lower end of the hollow piston, by which it is compressed and delivered to the chamber 49. The operation continues in this cycle.

It will be seen from the above-described arrangement that any of the sealing-oil that may pass from the pump into the condenser-coil will be made to pass up from the lower end of the latter through pipe 18 into the cylinder again, collecting in the oil-chamber 45, as described, and also any oil passing from the cylinder with the gas through pipe 23 into the cooler-coil 78 will be drawn from the bottom of the latter through pipe 51 to the suction-chamber of the compressor-cylinder, so that by this means any accumulation of oil in the condenser and cooler coils is effectually prevented.

On the driving-shaft 93 of the machine is a chain-wheel 94, geared, by means of a pitch-chain 95, with the chain-wheel 32 on the cam-spindle 31, that works the valves 19 and 22, as before described.

For charging the machine in the first instance with carbon dioxid or other vapor from a convenient source, such as a CO₂ cylinder, as also for making good leakages, a charging-valve 96 is provided, as shown at Fig. 45, which valve is constructed similar to the other stop-valves described. 97 is the pipe connected to the source of supply.

For the purpose of ascertaining whether the machine is properly charged with gas and the expansion-cock 77 between the condenser and cooler is properly adjusted a specially-marked thermometer 98 is fitted in the cap of the pump-chamber, so that by the increase or decrease of temperature shown by the thermometer it will be seen whether the charge of gas in the machine is deficient or otherwise. For facility of observation I prefer to mark the thermometer with a red line at the point "99" of the scale, where the rise of temperature would indicate that more gas is wanted in the machine or the expansion-cock required to be opened to a greater extent and with a blue line at the point "100," that would indicate that the gas-supply was ample and that the expansion-cock required slightly closing.

The suction-chamber 48 and discharge-

chamber 49 are each provided with a pressure-gage 101.

Having thus described the nature of this invention and the best means I know of carrying the same into practical effect, I claim—

1. In machinery for compressing and expanding gases or vapors for refrigerating purposes, a compressing-cylinder divided by a partition into an upper and lower chamber, a piston working in the upper chamber of the cylinder and having a piston-rod made partly tubular working through the partition, a lateral opening communicating with the hollow of the piston-rod which extends through the piston on the upper side of which it is closed by a valve held down by a spring, a valve apparatus communicating with the upper chamber of the cylinder below the piston and adapted to supply the same with charges of condensed gas during the working stroke of the piston, and to discharge the partly-expanded gas during the return stroke of the piston, means for supplying fully-expanded gas from the cooler of the machine to the bottom chamber of the cylinder whence it passes through the tubular piston-rod to the space above the piston during the return stroke of the latter, and is compressed during the following working stroke, substantially as and for the purpose described.

2. In machinery for compressing and expanding gases or vapors for refrigerating purposes, the combination of a compressing-cylinder 1, partition 3, piston 2, tubular piston-rod 4 4^{1/2}, working through the partition 3 and having an opening 8 communicating with the lower chamber 5 of the cylinder, a valve 6 closing the upper end of the tubular piston-rod, a chamber 10 with valve 9 into which the compressed gas is forced by the piston, a chamber 48 communicating on the one hand with the discharge-pipe of the cooler-coil and on the other hand by an opening 52 with said lower chamber 5 for supplying fully-expanded gas thereto, a chamber 49 communicating with the chamber 10 and with a pipe leading to the condensing-coil, valve apparatus 15 communicating with cylinder 1 by a passage 16, and containing firstly a chamber 17 with valve 19 operated by a cam device for admitting condensed gas to the cylinder through passage 16 and secondly a chamber 21 with valve 22 operated by a cam device 120 for discharging the partially-expanded gas from the cylinder through passage 16 to the cooler-coil of the machine, substantially as and for the purposes described.

3. In an apparatus for compressing gases or vapor for refrigerating purposes, the combination of a cylinder, a partition in said cylinder, a piston working on the upper side of said partition, a hollow piston-rod passing through said partition, a valve controlling the passage through said piston-rod, a passage communicating with said cylinder between said partition and said piston, means for supplying compressed gas or vapor to said pas-

sage, means for withdrawing said gas or vapor from said passage when it has become partially expanded beneath said piston, an inlet to said cylinder below said partition for expanded gas, and an outlet from said cylinder above said piston for said gas.

4. In an apparatus for compressing gases or vapor for refrigerating purposes, the combination of a cylinder, a partition in said cylinder, a piston working on the upper side of said partition, a hollow piston-rod passing through said partition, a valve controlling the passage through said piston-rod, a passage communicating with said cylinder between said partition and piston, a chamber for compressed gas or vapor communicating with said passage, a valve between said chamber and said passage, a second chamber communicating with said passage, a valve between said second chamber and said passage, an inlet to said cylinder below said partition for expanded gas, and an outlet from said cylinder above said piston for said gas.

5. In an apparatus for compressing gases or vapor for refrigerating purposes, the combination of a cylinder, a partition in said cylinder, a chamber in the upper end of said cylinder provided with an upwardly-opening valve, a piston working on the upper side of said partition, a hollow piston-rod extending through said partition, an upwardly-opening valve controlling the passage through said piston-rod, means for supplying gas or vapor to said cylinder between said piston and said

partition, means for withdrawing said gas or vapor from said cylinder after it has become partially expanded beneath said piston, an inlet to said cylinder below said partition for expanded gas, and an inlet to the lower part of said tubular piston-rod for said gas.

6. In an apparatus for compressing gases or vapor for refrigerating purposes, the combination with a condenser and a cooler; of a cylinder, a partition in said cylinder, a piston working in said cylinder above said partition, a hollow piston-rod extending through said partition, an upwardly-opening valve controlling the passage through said piston-rod, a passage leading from said condenser and entering said cylinder between said partition and said piston, a valve for controlling said passage, a passage leading from said cylinder between said partition and said piston to said cooler, a valve for controlling said last-mentioned passage, a passage leading from said cooler and entering said cylinder below said partition, a passage leading from the upper part of said cylinder above said piston to said condenser, and a valve for controlling said last-mentioned passage.

In testimony whereof I have hereunto set my hand in presence of two subscribing witnesses.
